LOUIS H. VON OHLSEN, OF NEW HAVEN, CONNECTICUT, ASSIGNOR TO THE SAFETY CAR HEATING & LIGHTING COMPANY, A CORPORATION OF NEW JERSEY

ELASTIC BELT

Application filed April 6, 1929. Serial No. 353,171.

This invention relates to elastic belts for the transmission of motion and power.

One of the objects thereof is to provide a simple, cheap and efficient article of the character described. Another object is to provide a practical elastic transmission belt which may be easily manufactured and which in use will prove both strong and durable. A third object is to provide a belt which will be practically free from certain undesirable characteristics that commonly develop in the use of belts of the general character above described. Other objects will be in part obvious and in part pointed out hereinafter.

The invention accordingly consists in the features of construction, combination of elements and arrangements of parts which will be exemplified in the structure to be herein-after described and the scope of the application of which will be indicated in the following claims.

In the accompanying drawing, in which is shown one of various possible embodiments of my invention,

Figure 1 is a side elevation of a belt constructed in accordance with my invention, and a pair of associated pulleys;

Fig. 2 is a view showing a section of the belt with a portion of the covering removed;

Fig. 3 is a cross-section of a belt showing its internal construction; and

Figs. 4 and 5 are sectional views illustrating the use of my belt with pulleys of different surface configurations.

Similar reference characters refer to similar parts throughout the several views of the drawing.

Now referring to the drawing in detail, a belt is shown generally at 1, surrounding in operative relation a pair of pulleys 2 and 3. By reference to Figs. 2 and 3, it will be seen that the belt 1 consists of a stranded elastic core 4 and a fabric covering 5. The manufacture thereof may be economically and practically accomplished by building up the core 4 in the following manner: A continuous strip of rubber elastic of any preferred cross-sectional shape is wound upon a mandrel of a diameter suitable for providing a

belt of the desired circumferential length. The winding is continued until the proper number of loops are formed to provide a stranded belt of the desired strength and elasticity. The strip of rubber is then cut 55 free from the core, and the two ends of that part of the strip now constituting the core are joined together by cement, or in any other suitable manner, as is indicated at 6 in Fig. 2.

There results then a continuous elastic core built up in the form of a plurality of coils produced by serially winding from a single strip of elastic material. The core thus constituted is then provided with an 65 outer covering or sheath 5 of cotton or other fabric material, which may consist of one or more layers, braided on the core continuously from a point at the beginning, along the circumferential length of the core, and back 70 to the said point, as is clearly shown in Fig. 1. The ends of the braided covering, where they meet, are then wrapped with cord or twine, as shown at 7 in Fig. 1.

It should not be inferred from the above 75 description that applicant limits his invention to the specific form of core described, for it is within the scope of his invention to employ a solid core or to construct the core in other fashion, as, for example, by grouping 80 together in one bundle, continuous elastic bands of the proper length, in numbers sufficient to give the requisite strength and tension.

Several important advantages accrue from 85 the employment of a fabric-covered belt having a stranded rubber core. Its manufacture is extremely simple and inexpensive. Belts of any required tension are easily provided and standardized. In use, the great flexibility of the completed belt is a decided advantage, for it may be made to conform closely to the friction surface of pulleys of widely differing shape. Fig. 4 shows how the belt adapts itself to pulleys having acutely 90 grooved surfaces, while Fig. 5 shows its equal adaptability for use with pulleys of more open conformation.

It has been found in practice that belts 100 consisting of a single piece of bare molded

rubber have a tendency to break down in service, through the development of transverse cracks and ultimate fracture. This undesirable feature is largely obviated by the use of solid or, preferably, stranded rubber cores protected by extensible fabric coverings. Then, too, when bare rubber is used, the friction developed along its surface of contact with the pulley tends to make it sticky and adherent to the surface of the pulley. This effect may be so pronounced as to cause the belt to wind up on the pulley and to put the associated mechanism out of action. By covering the core with an extensible fabric, the rubber is insulated against frictional heat, and is also protected from the deleterious effect of light and air, and is thus not only freed of its tendency to adhere to the pulley surface, but the rubber is so preserved as to give greater effective life to the belt.

It will thus be seen that the invention is well adapted to attain the ends and objects thereon in a thoroughly practical manner.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. A power transmission comprising, in combination, a drive-pulley, a driven pulley, and a transmission belt connecting said pulleys, said belt comprising an endless strip of elastic material forming a plurality of strands looped about said pulleys and adapted resiliently to transmit motion from said drive-pulley to said driven pulley.

2. A power transmission comprising, in combination, a drive-pulley, a driven pulley, and a transmission belt connecting said pulleys, said belt comprising a strip of elastic material wound in a plurality of turns about said pulleys and having its ends joined to form a continuous resilient member.

3. A power transmission comprising, in combination, a drive-pulley, a driven pulley, a transmission belt connecting said pulleys, said belt comprising an endless strip of elastic material forming a plurality of strands looped about said pulleys and adapted resiliently to transmit motion from said drive-pulley to said driven pulley, and a fabric covering said plurality of strands of elastic material for preserving said elastic material from deterioration due to friction.

4. A power transmission comprising, in combination, a drive-pulley, a driven pulley, a transmission belt connecting said pulleys, said belt comprising a strip of elastic material wound in a plurality of turns about said pulleys and having its ends joined to form

a continuous resilient member, and an extensible fabric covering said transmission member to permit stretching of said member but preventing deterioration thereof by reason of frictional heat.

5. A power transmission comprising, in combination, a drive-pulley, a driven pulley, and a transmission belt connecting said pulleys, comprising a stranded elastic core and a braided covering enveloping said core, said covering being of a nature to permit limited stretching of said core while protecting it from contact with said pulleys.

6. A power transmission comprising, in combination, a drive-pulley, a driven pulley, and an elastic transmission belt connecting said pulleys, comprising a body composed wholly of rubber and a braided covering enveloping said body, said covering being of a nature to permit limited stretching of said body while protecting it from contact with said pulleys.

In testimony whereof, I have signed my name to this specification this 1st day of April, 1929.

LOUIS H. VON OHLSEN.
